C. H. PAJEAU

BOWLING GAME APPARATUS

Filed Jan. 25, 1926

UNITED STATES PATENT OFFICE.

CHARLES HAMILTON PAJEAU, OF GLENCOE, ILLINOIS, ASSIGNOR TO TOY TINKERS, INC., OF EVANSTON, ILLINOIS, A CORPORATION OF ILLINOIS.

BOWLING-GAME APPARATUS.

Application filed January 25, 1926. Serial No. 83,703.

My invention relates to an apparatus for playing a game in which the scoring is done after the general manner as in bowling, and in its general objects aims to provide an inexpensive game apparatus for this purpose which will afford opportunities for the display of considerable skill by the players and which will introduce some of the same elements of fascination as found in regular 10 bowling.

In United States Patent No. 1,187,923, issued to me on June 20th, 1916 on a game apparatus, I have shown a bowling game apparatus employing a traveler member which 15 has a shaft adapted to span and roll upon two parallel elevated rails, and with means upon the shaft for storing up momentum and for rapidly halting the rotation of the shaft after this falls below a predetermined 20 speed. In the apparatus there disclosed, I employed a large number of movable members simulating the usual nine pins of a 25 bowling game, thereby introducing complications of manufacture and also depending in part on the resistance of the pins for 30 checking the movement of the traveler member. In my present apparatus, I employ only a single pin at each end of the apparatus and employ friction means as an aid for retarding the rotation of the shaft or 35 roller of the traveler member. I also dispose the pin in each case so that it can receive the direct impact of the momentum-storing portion of the traveler member and 40 so that an excessive travel of the traveler member beyond the point of upsetting the pin will lead the traveler member to a non-scoring position, while a too delicate contact with the pin will only shift or rock the 45 pin after the manner of a lightly touched pin in actual bowling.

Furthermore, my present apparatus provides a more simple construction, adapted to be rigidly assembled at the factory, and 45 one which can be cheaply manufactured with all stationary portions formed of sheet metal. Still further also some detailed objects will appear from the following specification and from the accompanying drawings, in which—

Fig. 1 is a perspective view of a game apparatus embodying my invention.

Fig. 2 is an enlarged plan view of the left-hand end portion of the same apparatus.

Fig. 3 is an enlarged transverse vertical 55 section, taken along the line 3—3 of Fig. 2.

Fig. 4 is a side elevation of the traveler member of the apparatus.

Fig. 5 is a plan view of one end of the apparatus, showing an obliquely played 60 traveler as halted without upsetting the bowling pin.

As here illustrated, my game apparatus includes a pair of parallel and preferably horizontal rails 1 and 2, supported at equal 65 heights above a base strip 3 which extends medially between the rails and which is disposed considerably lower than the rails. This base strip is here shown as secured to the bights of two U-shaped connecting members 4 and 5, each of which members has its arms secured respectively to the two rails 1 and 2, so as to support the rails in fixed relation to the base strip. The base-strip is provided near at least one end, and preferably 70 adjacent to both ends, with position-indicating means, such as circles 6 and 7, each adapted to define the initial position of a bowling pin 8 set upon the base strip.

Each rail is provided with markings 80 which preferably include a series of relatively short spaces numbered from 1 to 9 inclusive, the numbering being from the medial portion of the rail, and a considerably longer space numbered 10 adjacent to and 85 beyond the space numbered 9.

These numbered rail sections afford indications for scoring the halting point of a traveler which has been started from the opposite end of the rails with the intention of 90 upsetting the bowling pin and of halting the traveler within the indications of the space 10 adjacent to the upset pin. For this purpose, I provide a traveler having a shaft adapted to span the rails and to be rolled 95 upon the rails, and also having portions adapted to store momentum when the shaft is initially rotated by a twisting movement applied to both ends of the shaft by the fingers of the player. This traveler preferably 100 also has its momentum-storing means arranged so as to unbalance and speedily halt the traveler when its speed drops to a predetermined minimum, after the manner more

fully described in my said United States Patent No. 1,187,923.

In the drawings, the traveler includes a shaft 9 considerably longer than the width 5 of the track constituted by the pair of rails, a central ball fastened to the center of the shaft, and a plurality of arms 11 projecting radially from the ball 10 and symmetrically disposed about the axis of the shaft in a 10 plane transverse of that axis, the arms being of equal length and each having a head 12 at its outer end. Each arm has a momentum ball 13 slidable on it and of a diameter smaller than the distance between the head 15 of the arm and the central ball 10.

With the traveler thus constructed, a rapid rotation of the shaft will cause the momentum balls 13 to slide outward on the respective arms against the heads on the latter, 20 thereby balancing the traveler dynamically and acting after the manner of a fly-wheel for storing momentum. When the rotating shaft is then set down on the track, this momentum will cause the shaft to roll along 25 the rails. However, as soon as the speed of rotation becomes insufficient for causing centrifugal force to hold the balls against the heads of the arms, gravity will slide the uppermost one or two balls down against the 30 center ball, thereby unbalancing and rapidly halting the traveler.

Owing to this speedy halting, I can make the numbered spaces quite short in proportion to the diameter of the shaft of the traveler. However, a fair simulation of the difficulties encountered in actual bowling 35 make it desirable to interpose a relatively long stretch of track between the numbered sections and the track portion on which the 40 shaft is started. To provide this without making my apparatus unduly bulky, I employ momentum balls of a weight adapted to roll the shaft for a much greater length than that of the track and equip the traveler 45 with friction means for retarding its rotation. Thus, the illustrated traveler has a U-shaped sheet metal friction member 14 freely spanning the system of balls, with the shaft 9 extending loosely through the arms 50 of this U-shaped member. When the shaft is rotating, the friction of the arms on the shaft tends to retard the rotation and either arm may also slide against one end of the central ball 10 so as to add to the friction. 55 Moreover, if the traveler is not carefully started, it may roll oblique to the track, so as to cause an arm of the friction member to engage one of the rails, as shown in Fig. 5. Hence my simple arrangement not only 60 compensates for otherwise excessive momentum, thereby enabling me to shorten the length of the track traversed by the traveler before reaching the numbered sections, but also serves to penalize unskilled or care- 65 less players.

To prevent the traveler from rolling off either end of the track, I preferably provide suitable stop means, as for example, by providing both rails of the track adjacent to each end with notches 15 alining transversely of the track. These stop notches are preferably disposed adjacent to the designated pin positions, so as to increase the difficulty of scoring a 10 (or strike) indication, but the location of the stop means may be varied 70 according to the rules adopted for playing a game with this game apparatus. With the illustrated arrangement, a halting of the traveler by the notches may count as the equivalent of ditching a bowling ball, thereby nullifying the upsetting of the pin by the traveler; thus making it necessary for the player to halt the traveler back of the stop notches while still upsetting the pin, if he wishes to score a "strike". 75

With the same arrangement, the other numbered sections can score the corresponding members according to the section at which the traveler shaft stops, and a "spare" 80 can be scored when two consecutive non-strikes aggregate a given total, as for example ten or any number from ten to fifteen. To make the indications more easily discerned, I preferably place section-indicating numerals not only on the tops of the rails 85 but also on the rail sides. To increase the difficulty of scoring "strikes", I may also make the momentum balls of such a limited diameter that they can enter between the properly positioned pin and one of the rails 90 if the traveler is at one side of the track, as shown for example in Fig. 5.

As a desirable construction, I preferably make each of the rails of an angular section and form the supports 4 and 5 of channel-sectioned metal disposed with the channels backs outward so that each channel back can readily be secured flatwise to the depending web of the adjacent rail. I also desirably form the middle portion of the bight of each 105 support 4 and 5 so as to form an arch fitting snugly into the base strip 3 which is of an inverted channel section, thereby permitting a single rivet 16 to secure each supporting member rigidly to the base strip. 110

For a table game apparatus, I preferably provide similar sets of numbered sections and pin-spotting indices at each end of the track, so that the game can be played alternately from opposite ends of the apparatus. 115 However, I do not wish to be limited to the employment of my invention in a double-ended apparatus, nor to the above described desirable details of construction and arrangements, since many variations might obviously be made without departing either from the spirit of my invention or from the appended claims. 120

I claim as my invention:

1. In a game apparatus, a pair of spaced 125

- rails, and a traveler member adapted to be rolled upon the rails; the traveler member including a roller spanning the rails, momentum-acquiring means carried by the roller for continuing rotation imparted to the roller, and friction means carried by the roller for retarding rotation thereof.
2. In a game apparatus, a pair of spaced rails, and a traveler member adapted to be rolled upon the rails; the traveler member including a roller spanning and resting upon the rails, momentum-acquiring means carried by the shaft for continuing rotation imparted to the roller, and friction means carried by the roller for retarding rotation, the friction means being adapted to engage either of the rails.
3. In a game apparatus, a track, a roller movable upon the same, means carried by the roller for dynamically balancing the latter when rotated at a predetermined minimum speed and for dynamically unbalancing the roller when rotating at a speed below that minimum and a friction member rotatably mounted on the roller for retarding rotation of the latter.
4. A game apparatus as per claim 3, in which the friction member comprises a yoke having perforations in its arms through which the roller extends.
5. In a game apparatus, a pair of rails, a roller movable upon the same, momentum-storing means carried by the roller and disposed between the rails, and a friction member journaled on the roller and having its journaling portions respectively disposed at opposite sides of the momentum-storing means and respectively adapted to engage either side of the momentum-storing means.
6. In a game apparatus, a track, a rotatable traveling member having a member adapted to roll on the track, and two speed-retarding means carried by the traveling member; one of the said means being continuously operative while the traveler is rotating, the other of the said means being operative only when the traveling member is rotating below a predetermined speed.
7. In a bowling game apparatus, a pair of elevated rails, a normally upright pin disposed between the rails at one end thereof, a pin support provided medially between the rails with a spot marking defining the position of the base of the pin, means rigidly connecting the pin support to the rails; and a rotatable traveling member including lateral portions adapted to roll respectively on the two rails and a medial portion adapted to engage the pin, the medial portion having a part thereof of such a size as to enter between the pin and one of the rails.
8. In a bowling game apparatus, a pair of elevated rails, a normally upright pin disposed between the rails at one end thereof, and a rotatable traveling member including lateral portions adapted to roll respectively on the two rails and a medial portion adapted to engage the pin, the medial portion having a part thereof of such a size as to enter between the pin and one of the rails.
9. In a bowling game apparatus, a pair of aligned U-shaped supports having their bights adapted to seat on a table, a base strip secured to the said bights and marked near each end with an indication for defining the position of a bowling pin, a loose bowling pin having a base adapted to seat on either of the said indications, a pair of elevated rails each secured to one shank of each support, the said rails being laterally equidistant from the two marked indications and extending beyond the said indications, and a traveler member adapted to be rolled upon the rails from either end to upset the bowling pin when the latter is positioned on the indication near the opposite end of the strip.
10. In a bowling game, a rigid structure including a pair of horizontal and laterally spaced rails and a pair of pin supports, respectively adjacent to the opposite ends of the rails, each pin support being disposed below and between the rails and having a marking to indicate a definite position for a bowling pin; a bowling pin standing on one of the said markings; and a traveler member including a roller spanning and resting upon the rails, and means carried by the roller for storing momentum, the traveler member having a portion thereof disposed between the rails and disposed for engaging the bowling pin when the roller is rolled upon the rails toward the end of the rails adjacent to which the bowling pin is disposed.
11. A bowling game as per claim 10, including means on the rails adjacent to the bowling pin for halting the roller if the latter reaches the said means with less than a predetermined momentum, the said means being insufficient for effecting such halting if the roller has a greater momentum.
12. In a bowling game, a pair of elevated and laterally spaced and substantially horizontal rails, means for supporting the rails, a pin support fast with respect to the rails and having a marking denoting the proper position for a bowling pin, the part of the support having the said marking being below and between the rails; a bowling pin standing on the said marking; and a traveler member including a roller spanning and resting upon the rails, and momentum-storing means carried by the roller and disposed between the rails and adapted to engage the bowling pins; one of the rails

having a series of spaced markings for indicating positions in which the roller is halted before the momentum-storing means have engaged the bowling pin.

13. A bowling game as per claim 12, including means upon the rails for halting the traveler member when the latter has

traveled for a predetermined distance after its momentum-storing means have engaged the bowling pin.

Signed at Evanston, Illinois, Jan. 20, 1926.

CHARLES HAMILTON PAJEAU.
